UNITED STATES PATENT OFFICE.

CARL WHEELER MOTT, OF ROCK FALLS, ILLINOIS, ASSIGNOR TO THE RICH MANUFACTURING COMPANY, OF STERLING, ILLINOIS.

ANIMAL TOY.

Application filed February 18, 1926. Serial No. 89,159.

This invention relates to toys of that character in which the figure of an animal is mounted upon a wheeled platform, the body of the figure and the legs thereof being moved as the platform is pulled over the floor or ground.

The general object of my present invention is to provide a toy of this character in which the wheeled platform supports the figure of the animal, said figure having at least one pair of depending legs which are pivoted to the body and provide means whereby these legs may be swung back and forth as the toy is moved and further provide means whereby the body may be oscillated at the same time.

A further object is to provide a construction of this character comprising a body having two pairs of opposed legs and provide means whereby the body may be tilted vertically and whereby the legs may be moved alternately, said means being operated by a crank shaft upon which certain of the traction wheels are mounted.

My invention is illustrated in the accompanying drawings wherein:—

Figure 1 is a side elevation partly in section of an animal toy constructed in accordance with my invention;

Fig. 2 is an underside plan view on the line 2—2 of Figure 1, but showing the legs in a medium position;

Fig. 3 is a fragmentary section on the line 3—3 of Figure 1;

Fig. 4 is a section on the line 4—4 of Figure 1;

Figures 5 and 6 are diagrammatic perspective views showing the position of the legs and actuating parts therefor as the position of the body is changed.

Referring to these drawings it will be seen that I have illustrated a platform 10 having front wheels 11 mounted in any suitable manner upon the platform, and rear wheels 12 mounted upon a transverse axle 13, the middle portion of which is cranked as at 14, the platform being cut out to accommodate this cranked portion. The body 15 of the animal, which in the present embodiment simulates an elephant, is pivotally supported upon an upstanding rod 16. This rod passes downward through the platform and is screw-threaded at its lower end and engaging the rod are two nuts 17 which embrace the plat-

form 10 and are clamped thereagainst to hold the rod rigid.

The body of the animal is formed with a bore 18 and disposed within this bore is a U-shaped bushing 19, the upper end of the supporting rod 16 being pivoted to this bushing in any suitable manner as at 20, so that the body may be oscillated upon this supporting rod. At the rear the body is provided with a depending rod 21 which is telescopically mounted within a tubular sleeve 22 pivotally mounted upon the crank 14. This rod 21 is preferably of such length that as the crank shaft rotates the rod 21 will be shifted rearward and upward and then remain stationary while the crank 14 moves downward and until the crank 14 commences to rise to a predetermined position. Pivotally mounted upon the sides of the body 15 are the fore legs 23 and the hind legs 24. These legs are pivoted upon the body in any suitable manner. For the purpose of oscillating these legs as the body is moved, the fore legs are provided with oppositely disposed sockets 25 formed by metallic bushing forced into the wood of the legs and the hind legs are provided with like sockets.

Mounted upon depending pins 26 are the cross bars 27 and 28, the ends of which cross bars enter the sockets 25 in the respective legs. For the purpose of tilting these cross bars I pivotally mount upon the supporting rod 16 the rod 29 which is preferably pivotally mounted upon this supporting rod 16 for slight oscillatory movement, by forming a loop 30 in this rod 29 which surrounds the supporting rod 16. The forward end of this rod 29 is angularly bent downward, as at 31 and passes through the rod 27 on one side thereof and the rear end of the rod 29 is angularly bent and passes downward through an opening formed in the cross bar 28 preferably on the other side of the cross bar from the first named angular portions 31. These angular portions 31 constitute fulcrums for the cross bars.

It will be obvious that these cross bars will oscillate in opposite directions and being connected to the legs as they are, the two legs on one side of the body will move in opposite directions and the opposed legs of each pair will move in opposite directions. Thus the legs on one side will swing to-

- ward each other while the legs on the other side will simultaneously swing away from each other, thus simulating the running or walking gait of an elephant or like animal.
- 5 Preferably though not necessarily, a rail 32 is mounted upon the platform which extends partially around the same. The body of the animal, of course, is painted to more or less simulate an elephant or painted in attractive colors.
- In the operation of this device as the rear end of the body lowers the rear pin 26 moves toward the support 16 and the forward pin 26 moves away from the support 16. The 15 angularly bent ends 31 of the rod 29 constitute fulcrums for the respective cross bars 27 and 28 and inasmuch as these fulcrums are disposed on opposite sides of the pins 26 it follows that the cross bars will be rocked in opposite directions upon a downward movement of the body and again move in opposite directions but reversely to the movement upon an upward movement of the body. The pivotal support 30 for the rod 25 29 simply accommodates the slight lateral swing of this rod. The oscillations of the cross bars are secured by the longitudinal backward and forward movement of the pins 26.
- 20 I do not wish to be limited to the particular form of the animal body or to the particular details of construction as these might be modified without departing from the spirit of the invention as defined in the appended claims, but it will be seen that mechanism which I have provided is very simple, that it may be very cheaply made and that it is entirely effective for the purpose intended. The body may be cut from one 25 single thickness of wood, the legs from a thickness of thinner wood and it will be further seen that all of the parts may be very cheaply put together.
- 30 I claim:—
- 45 1. A toy comprising a support having traction wheels, an animal figure pivotally supported thereon for movement in a vertical plane and having transversely opposed legs pivoted to the body, a vertically disposed pivot mounted on the body, and a transversely extending member mounted on said pivot and engaging at its opposite ends with the legs, and means connected to said wheels for acting as the toy is propelled to 50 rock the body upon its pivot and rock said transversely extending member to thereby cause the oscillation of the legs.
- 55 2. A toy comprising a wheeled support, an animal figure supported thereon having forward and rearward pairs of depending legs pivoted to the body, vertically disposed pivots mounted upon the body between said legs, cross bars, one for each pair of legs having their extremities operatively engaged 60 with the legs, the cross bars being mounted

upon said pivots for movement of oscillation in a horizontal plane, means acting as the body is propelled for oscillating the body in a vertical plane and means operatively connecting one of said cross bars to the other cross bar, and causing the cross bars to oscillate simultaneously in opposite directions as the body is tilted.

3. A toy comprising a wheeled platform, an animal figure, a support extending upward from said platform and upon which said figure is mounted for vertical oscillation, a cranked axle having traction wheels mounted upon the platform, a member connecting the cranked axle to one end of the figure to thereby cause the figure to be oscillated as it is drawn over the ground, cross bars pivotally supported upon the body, the opposed pair of legs having sockets into which the ends of the cross bars extend, a rod pivotally supported intermediate its ends for oscillation in a horizontal plane and pivotally connected to the cross bars, the pivotal supports for said cross bars extending from the body and engaging said cross bars each at a point to one side of the point of engagement with the rod.

4. In a toy of the character described a platform, a cranked shaft mounted thereon, supporting traction wheels, a support extending from the platform, a body pivotally mounted adjacent its forward end upon said support for movement in a vertical plane, means connecting the rear ends of the cranked shaft to the rear end of the body to thereby tilt the body upon its pivot, forward and rear pairs of legs pivoted to the body and having confronting sockets on their inner faces, cross bars one for each pair of legs and having their extremities disposed in said sockets, a fulcrum member for said cross bars comprising a longitudinally extending rod mounted upon the supporting member for oscillation in a horizontal plane and having downwardly turned ends extending through and pivotally engaging the cross bars, and pins extending downward from said body and extending through the cross bars, the pin on the forward end of the body being disposed on one side of the fulcrum for that cross bar and the pin on the rear end of the body being disposed on the opposite side of the corresponding fulcrum from the first named pin.

5. A toy of the character described comprising a wheeled platform, an animal figure, a support extending upward from said platform and upon which said figure is mounted for vertical oscillation, a cranked axle mounted upon the platform operatively driven from the wheels thereof, a member connecting the cranked axle to one end of the figure to thereby cause the figure to be oscillated as it is drawn over the ground, cross bars pivotally supported upon the

body, the opposed pairs of legs having sockets into which the ends of the cross bars extend, and a rod pivotally supported intermediate its ends for oscillation in a horizontal plane and pivotally connected to the cross bars.

6. A toy of the character described including a wheeled support, a body pivotally mounted upon said support for oscillation in a vertical plane, forward and rear pairs of legs pivoted to the body and having confronting sockets on the inner faces, cross bars, one for each pair of legs and having their extremities disposed in said sockets, pivots for said cross bars extending down-

ward from the body and a fulcrum member for said cross bars comprising a longitudinally extending rod mounted for oscillation in a horizontal plane, and having its ends pivotally engaged with said cross bars, the 20 point of pivotal engagement for the cross bar on the forward end of the body being disposed on one side of the fulcrum for that cross bar and the point of pivotal engagement for the rear cross bar being disposed on the opposite side of the corresponding fulcrum from the first named pivoted point. 25

In testimony whereof I hereunto affix my signature.

CARL WHEELER MOTT.
